(57) **CLAIM**

The ornamental design for a folding structure for storage, shelter, and plant growing, as shown and described.

DESCRIPTION

FIG. 1 is a top, side perspective view of a first embodiment of a folding structure for storage, shelter, and plant growing, showing my new design;

FIG. 2 is a right side elevational view of FIG. 1, the left side elevational view being identical thereto;

FIG. 3 is a rear elevational view of FIG. 1, the front elevational view being identical thereto;

FIG. 4 is a top plan view thereof.

FIG. 5 is a right side perspective view of a second embodiment of the folding structure for storage, shelter, and plant growing;

FIG. 6 is a right side elevational view thereof;

FIG. 7 is a left side elevational view thereof;

FIG. 8 is a rear elevational view thereof;

FIG. 9 is a front elevational view thereof;

FIG. 10 is a top plan view thereof.

FIG. 11 is a side perspective view of a third embodiment of the folding structure for storage, shelter, and plant growing;

FIG. 12 is a right side elevational view thereof, the left side elevational view being identical thereto;

FIG. 13 is a front elevational view thereof; the rear elevational view being identical thereto;

FIG. 14 is a top plan view thereof; and,

FIG. 15 is a perspective view thereof, showing the folding structure for storage, shelter, and plant growing in a partially folded condition.
